(57) **CLAIM**

The ornamental design for a cleaning pen for earphone, as shown and described.

DESCRIPTION

FIG. 1 is a perspective view of a cleaning pen for earphone showing the new design;

FIG. 2 is a front elevation view thereof;

FIG. 3 is a back elevation view thereof;

FIG. 4 is a left-side view thereof;

FIG. 5 is a right-side view thereof;

FIG. 6 is a top plan view thereof;

FIG. 7 is a bottom plan view thereof;

FIG. 8 is a perspective view thereof;

FIG. 9 is a perspective view thereof in a first extended position;

FIG. 10 is another perspective thereof in a second extended position;

FIG. 11 is a perspective view thereof in an unfolded position; and,

FIG. 12 is an exploded view of FIG. 10.

The broken lines depict portions of the article that form no part of the claimed design.

1 Claim, 12 Drawing Sheets
